UNITED STATES PATENT OFFICE.

SAMUEL E. BEELER, OF WAYNESBORO, PENNSYLVANIA, ASSIGNOR TO FRICK COMPANY,
OF WAYNESBORO, PENNSYLVANIA, A CORPORATION.

TRACTION-WHEEL.

1,142,227.

Specification of Letters Patent. Patented June 8, 1915.

Application filed July 1, 1911. Serial No. 636,542.

To all whom it may concern:

Be it known that I, SAMUEL E. BEELER, a citizen of the United States, residing at Waynesboro, in the county of Franklin and State of Pennsylvania, have invented certain new and useful Improvements in Traction-Wheels, of which the following is a specification.

My said invention consists in an improved form of fill-block for traction wheels whereby such a block is provided of an inexpensive character and one which may be readily and rigidly secured in place, all as will be hereinafter more fully described and claimed.

Referring to the accompanying drawings which are made a part hereof and on which similar reference characters indicate similar parts, Figure 1 is a face view of a portion of a traction wheel provided with my said fill-block, Fig. 2 an edge view thereof, and Fig. 3 a sectional view.

In said drawings the portions marked A represent the rim of the wheel and B the fill-block. The traction wheel, in itself, is, or may be, of any approved form or construction preferably having a rim with a wide face armed with cleats *a* arranged thereon a suitable distance apart and extending at an angle in relation to the face of the wheel, either "staggered" or the entire width of the wheel, as is usual. The cleats *a* are secured by rivets *a'* which extend through perforations in said cleats and corresponding perforations in the rim A. At the points in said cleats immediately surrounding said perforations, or rivet holes, said cleats are preferably spread somewhat and formed with bulged out portions in their edges.

The fill-blocks B are of the form best shown in Fig. 3, being preferably hollow on their under sides with ribs, to render them sufficiently stiff for the purpose, and with smooth outer faces. The edges are tapered to fit between the tapered edges of the cleats *a* and have curved recessed portions to fit

around the curved bulged out portions on the edges of the cleats so that when said fill-blocks are placed in position they are held from lateral movement by the engagement between said recesses in the fill-blocks and the bulged out portions of the cleat. Bolts *b* are provided which extend through perforations in the fill pieces, the heads of the bolts being countersunk therein to be flush with their surfaces, and nuts being mounted on the underside for clamping said fill pieces in position. I preferably provide two of said nuts, *b'* being a clamping and holding nut and *b''* a jam nut for holding said nut *b'* in position. By this means a fill-block is provided which is inexpensive to construct, comparatively light and may be attached quickly and securely with but a single bolt to hold it in position, the engagement between the edges of the fill-block and the edges of the cleats being preferably of an inter-locking character and serving as a principal support therefor.

Having thus fully described my said invention, what I claim as new and desire to secure by Letters Patent, is:

A traction wheel comprising a rim, cleats secured to said rim to extend obliquely across the face thereof and parallel with each other and formed with bulged out retaining portions on their oblique edges, a fill block adapted to fit between two adjacent cleats and formed with recesses in its edges of a form adapted to fit around the retaining bulged out portions of the cleats, and means for detachably securing said fill block to said rim, substantially as set forth.

In witness whereof, I have hereunto set my hand and seal at Waynesboro, Pennsylvania, this 19 day of June, A. D. nineteen hundred and eleven.

SAMUEL E. BEELER. [L. S.]
